United States Patent Office

Des. 211,236
Patented June 4, 1968

211,236

BOTTLE

Ernest L. Du Pree, New York, N.Y., assignor to Schenley
Industries, Inc., New York, N.Y., a corporation of Delaware

Filed Aug. 2, 1967, Ser. No. 8,095

Term of patent 14 years

(Cl. D9—112)

FIG. 2

FIGURE 1 is a side elevational view of a bottle embodying my new design, the side of the bottle not shown being identical in appearance with the side of the bottle shown;

I claim:

The ornamental design for a bottle, as shown and described.
